TIME-DELAY RELAY CIRCUITS

George E. Brode, Newark, N. J., assignor to Federal Telephone and Radio Corporation, New York, N. Y., a corporation of Delaware

Application November 10, 1947, Serial No. 784,985

2 Claims. (Cl. 175—320)

1

My invention relates to time delay relay circuits and is particularly directed to circuits for accurately measuring a predetermined time interval after an initiating electric pulse.

There are numerous applications of time delay circuits. In industrial counting mechanisms, for example, a power relay must be actuated a given time after actual counting by a phototube or a trigger finger. Heretofore, the necessary time delay has been obtained by ordinary slow release relays using direct current power supplies. There is not only no control over the length of the delay period, but it is often inconvenient to obtain the direct current. The copper-oxide type rectifier is undesirable because of size and temperature limitations while vacuum tube rectifiers employing hot cathodes are not suitable because of the time delay involved in raising the cathode to operating temperature and because, for intermittent operation, it is costly to maintain a cathode hot. Alternating current-operated relays have obvious advantages.

The general object of my invention is an improved time delay circuit.

A more specific object of my invention is a time delay circuit which is simple in construction, adjustable as to time delay, and is economical and reliable in operation.

A still more specific object of my invention is a time delay circuit that is entirely operable on alternating current.

The scope of my invention is particularly defined in the appended claims and exemplary embodiments thereof are described in the following specification and shown in the accompanying drawing in which

Figs. 1 and 3 are circuit diagrams of two of said embodiments, and

Figs. 2 and 4 are time-sequence graphs of important voltages of the circuits of Figs. 1 and 3, respectively.

At 1 is shown a push-button switch which is arbitrarily chosen for illustration here to exemplify any switch or key that serves to momentarily close a circuit, the closure of which is to be followed by the actuation of certain relays in predetermined time sequence and at predetermined intervals. Switch 1 may, for example, comprise the contacts of a photoelectric-actuated relay of an industrial counter, and the sequential operations to follow may include motor start-stop switching. At 2 is represented a voltage source which according to my invention is alternating current. At 3 is an electromagnetic relay of conventional design with winding 4 and

2

normally open contacts 5, the winding and contacts being electrically connected in series. Relay 6 comprises winding 7 and the normally closed contacts 8. With contacts 5 in series with winding 4, contacts 5 lock-up once winding 4 is energized. Hence, switch 1 is placed across the contacts 5.

The first and instantaneous result of the closure of contacts 5, is the ignition of a discharge in the gaseous discharge device 9, the anode-cathode space being connected across the voltage source 2 through contacts 5. The control or starter electrode 10 may be a grid or a pointed igniting electrode and the cathode 11 may be of the cold type such as a cold oxide coated member or a pool of mercury. Anode potential is applied to the starter electrode 10 through resistor 12. The discharge current will cause a considerable voltage drop across cathode resistor 13, the half-wave pulses being smoothed as desired with condenser 14.

Condenser 15 and resistor 16 are connected in series and across the cathode resistor, the time constant of this network being adjusted to any desired value by adjustment of the values of the condenser 15 and/or the resistor 16. It will more fully appear hereinafter that the time constant of this capacity-resistance network easily predetermines the delay time of the system.

The second gaseous discharge device 17 is also connected across the source 2 through contacts 5. Ignition of a discharge in tube 17, and energization of the winding 7, must, however, await the proper potential on the control electrode 18. The condenser 15 is connected directly across the grid-cathode of tube 17, so that this igniting potential is determined by the charge of the condenser 15. Hence, ignition of a discharge in tube 17 is delayed for an interval of time determined by the time constant of the capacity-resistance network 15—16. Energization of winding 7 opens the normally closed contacts 8 of relay 6 which in turn deenergizes the winding 4, allowing contacts 5 to fall open.

A utilization circuit, or circuit to be controlled, may comprise a relay winding in any portion of the circuits shown which carries current only during the delay period, or conveniently, auxiliary contacts may be operated by the armature of either relay 3 or 6. In Fig. 1, for example, contacts 19 in the circuit to be controlled are operated by the armature of relay 3. The contacts 19 may be normally open or normally closed, as desired.

The sequence of operations of the circuits of

Fig. 1 may be diagrammed as Fig. 2. Switch 1 is at least momentarily closed and relay 3 locked up. Contacts 19 close, assuming these contacts are normally open. A discharge in tube 9 is immediately initiated and condenser 15 starts charging. After a predetermined time grid 18 ignites tube 17, whereupon winding 1 opens contacts 8. The then deenergized winding 4 releases and opens contacts 5 and 19. That is, contacts 19 operate at the beginning and at the end of this sequence, the time interval being measured by the size or capacity of condenser 15 or the ohmic value of resistor 16, either of which is easily adjusted. The same sequence follows each time switch 1 is closed.

The circuits of Fig. 3 are in all respects the same as the circuits of Fig. 1, but with the addition of relay windings 20 and 21 specifically for operating contacts 19. The contacts 19, of the circuit to be controlled, are here mechanically connected with a common armature for the two windings 20 and 21 so that energization of either winding will serve to actuate contacts 19. The windings 20 and 21 may be placed on separate or on a common core as desired. Winding 20 is connected across the voltage source 2 back of switch 1 so that at the instant switch 1 is closed, the armature of contacts 19 pulls up. The other winding 21 is connected in series with resistor 22 and the back and normally closed contacts 23 of relay 3 across condenser 15. Thus, with contacts 23 closed, and with condenser 15 charged, winding 21 may also energize and pull up the armature of contact 19.

In operation, closure of switch 1 locks up relay 3 as in Fig. 1, and the sequence of operations graphically represented in Fig. 4 follows. Contacts 5 close and contacts 23 open. In addition to initiation of a discharge in tube 9, winding 20 is immediately energized and condenser 15 starts charging. After a predetermined time, condenser 15 is charged to a sufficient potential to ignite tube 17, whereupon winding 1 opens contact 8, deenergizing winding 4 and releasing its armature. As contacts 5 open, contacts 23 close, connecting the now charged condenser 15 across the winding 21, and transferring the holding force on the armature and contact 19 from winding 20 to winding 21. It is assumed in this illustration that contacts 23 make before contacts 5 break so that there is a time overlap of magnetization of windings 20 and 21. Winding 21 will hold until condenser 15 is nearly discharged, the discharge time being determined, for a given charge, by the value of resistance 22, and winding resistance, in the discharge circuit. Accordingly, the total delay period is measured by the charging time plus the discharging time of condenser 15.

While in some applications of my time delay circuit, an overlap of the energization pe-

riods of windings 20 and 21 may be desired sufficiently to insure against release of the armature and contact 19, in other applications, a hiatus may be required. For the overlap, a make-before-break sequence at contacts 23 and 5, is provided, and for a hiatus or idle period a make-after-break sequence at contacts 23-5 is provided. A dashpot or other one-way drag may be added to the armature if an especially long time interval is required.

My improved time delay circuit operates on commercial alternating current, requires no stand-by or idling current, is easily adjustable, is simple and inexpensive in construction, and is reliable in operation.

I claim:

1. A time delay circuit comprising a voltage source, a lock up relay, said relay having at least one winding connected across said source, 20 at least one pair of contacts controlled by said relay, said winding being in series with said pair of contacts, said source connected to said relay for holding closed said contacts, a normally open switch across said contacts of said relay, first and second discharge tubes connected in parallel across said source through said pair of contacts, a resistor in the cathode circuit of said first discharge tube, a capacity-resistance network connected in series across said cathode resistor, a second relay in the anode circuit of said second tube, normally closed contacts associated with said second relay, said normally closed contacts being connected in series with the winding of said lockup relay.
2. A time delay circuit according to claim 1 and further comprising third and fourth relay windings, and a further set of contacts controlled by said first mentioned winding, said third winding being connected across said source, said fourth winding being connected in series with said capacity-resistance network, said third and fourth windings being alternately energized correspondingly with the energization and deenergization of said first mentioned winding.
